UNITED STATES PATENT OFFICE.

JOHN R. WHEELER, OF WEST MYSTIC, CONNECTICUT, ASSIGNOR TO THE STANDARD MACHINERY CO., OF MYSTIC, CONNECTICUT, A CORPORATION.

FEED MECHANISM FOR EMBOSSED PRESSES.

Application filed May 25, 1926. Serial No. 111,508.

I do hereby declare the following, when taken in connection with the accompanying drawings and the characters of reference marked thereon, to be a full, clear, and exact description of the invention, and which said drawings constitute part of this application, and represent, in—

Fig. 1, a view in front elevation of an embossing press equipped with my improved feed-mechanism;

Fig. 2, a view thereof in side elevation;

Fig. 3, a broken detail view in side elevation of the two-part feed-slide and feed-cam of my improved mechanism, the parts being shown in the positions due them at the completion of their forward or feeding movement;

Fig. 4, a longitudinal sectional view thereof on the line 4—4 of Fig. 3;

Fig. 5, a broken detail view in edge elevation of the feed-cam, showing the plunger in its operative position;

Fig. 6, a similar view, but showing the plunger in its retired or inoperative position;

Fig. 7, a view in elevation corresponding to Fig. 3, and showing the parts in the positions due them when the uncoupling-slide is moved forward to uncouple the two feed-bar members from each other; and

Fig. 8, a similar view showing the inner feed-bar member telescoped into the outer feed-bar members, as a result of the uncoupling action shown in Fig. 7 and the subsequent movement of the feed-cam.

My invention relates to an improvement in feed-mechanism for embossing presses which are designed to emboss various articles, such as book covers, novelties, etc.

In the production of embossed articles, such as book covers in particular, it has been found that a superior finish is obtained by subjecting the article to relatively moderate repeat actions of the embossing dies, rather than to a single severe action thereof.

The object of my invention is to produce a feed-mechanism for embossing presses which will, at the option of the operator, permit the article being fed to be subjected to either a single or double action of the embossing dies.

With this object in view, my invention consists in a feed-mechanism for embossing presses which is synchronized with the action of the embossing dies thereof and which is characterized by its convertibility from a

single action to what I shall call a "skip action" feed-mechanism, whereby the article being embossed may be subjected to either a single or a repeat action of the embossing dies.

In the embodiment of my invention herein shown, it is applied to an embossing press of well-known characteristics and generally designated by the numeral 10. This embossing press comprises an upper stationary die-block 11 carrying an upper die 12 and a vertically-movable die-block 13 carrying a lower die 14. The lower die-block 13 is moved toward the upper die-block 11 so as to press the article to be embossed between the upper and lower dies 12 and 14, by means of a toggle 15 operated by a drive-shaft 16, to which it is connected by an arm 17—all in the ordinary and well-known manner of such presses. To provide for feeding the blanks 18 onto the vertically-movable die-block 13, I provide a reciprocating feed-plate 19 which is carried by two corresponding horizontally-arranged racks 20 mounted in a vertically-adjustable table 21 upon which the pile 22 of blanks is stacked. The racks 20 are respectively meshed into by two complementary pinions 23 mounted on a shaft 24 having bearing in the table 21. At its outer end the shaft 24 is provided with a pinion 25 meshed into by a reciprocating rack 26 formed at the forward end of an outer feed-bar member 27, which is recessed at 28 for the reception of the complementary inner feed-bar member 29. The feed-bar member 29 is provided with a slot 30 receiving a guide-stud 31 extending outward from the drive-shaft 16 aforesaid, and is provided with a roller 32 entering the groove 33 of a feed-cam 34 mounted upon and driven by the drive-shaft 16, so that the movement of the cam is synchronized with the toggle mechanism.

Normally, the feed-bar members 27 and 29 are coupled together to act as a unit by means of two wedge-shaped latches 35 entering notches 36 in the inner feed-bar member 29 and urged thereinto by latch-springs 37 which, together with the latches 35, are mounted in off-setting recesses 38 formed in the outer feed-bar member 27. When the latches are entered into the notches 36, as clearly shown in Figs. 2 and 3, the two feed-bar members 27 and 29 will be reciprocated as a unit by the cam 34 and will, through the medium of the rack 26, pinion 25, shaft 110

24, and pinions 23, cause the feed-racks 20, and hence the feed-plate 19, to be reciprocated once for every revolution of the drive-shaft 16, and hence once for every embossing action of the dies 12 and 14. To provide for uncoupling the feed-bars 27 and 29 from each other, so that the feed-plate 19 will remain idle for one revolution of the drive-shaft 16 and thus permit a blank to remain between the embossing dies 12 and 14 during two complete embossing actions thereof, I provide the feed-bar 29 with a recess 39 in its outer face for the reception of an uncoupling-slide 40 having inclined latch-engaging faces 41 at its forward end and a roller 42 at its rear end. The slide 40 is normally urged to its rearward or retired position, in which its roll 42 engages with a two-pointed unlatching cam 43 by means of a spring 44. The two-pointed cam is rigidly attached to the outer end of a short shaft 45 extending transversely through the feed-bar member 29 and which, at its opposite end, is provided with a four-pointed star-wheel 46, which latter is adapted to be engaged by a plunger 47 carried in an arm 48 off-setting from the cam 34. The plunger 47 aforesaid is normally maintained in its extended position in which it is adapted to engage one of the points of the star-wheel 46 during each revolution of the feed-cam 34 by means of a spring 49 encircling its stem 50, which at its inner end is provided with a finger-button 51 by means of which it may be retracted into its inoperative position. To provide for holding the plunger 47 in its retired position against the counter-urge of its spring 49, the plunger-stem 50 is provided with a transverse pin 52 which normally is entered into a clearance-slot 53 formed in the rear face of the arm 48, as clearly shown in Fig. 5, but which may be engaged with the extreme rear face of the arm by drawing it inward and imparting to it a quarter-turn, as clearly shown in Fig. 6.

To provide for the vertical adjustment of the table 21, the same is mounted on opposite ends on brackets 54, each of which is provided on its outer face with lugs 55 and 56 adapted to receive a feed-screw 57 which is threaded into the lower lug 56, so as to raise and lower the table when it is rotated. Each feed-screw 57 is provided at its lower end with a spiral pinion 58 meshing into one of two spiral pinions 59 mounted upon a transverse shaft 60. The shaft 60 serves to insure the uniform concurrent adjustment of both ends of the table 21.

Having fully described the nature of my invention, I shall now proceed to describe its operation. With the parts in the positions in which they are shown in Fig. 1, the two-feed-bar members 27 and 29 are coupled together by means of the coupling-latches 35 for movement as a unit, and the subsequent

half-rotation of the drive-shaft 16 will move them forward to the positions shown in Figs. 3 and 4, with the effect of moving the feed-plate 19 inward, and pushing another blank 18 over the die 14. The next half-revolution of the cam will effect the retirement of the feed-slide, during which movement the blank will be acted upon by the dies 12 and 14.

Near the conclusion of the full revolution of the feed-cam as just described, the plunger 47 will engage with one of the points of the star-wheel 46 and impart to it a quarter-revolution, whereby the unlatching-cam 43 is likewise given a quarter-turn with the effect of moving the unlatching-slide 40 forward into the position in which it is shown in Fig. 7, whereby its faces 41 will retract the latches 35 from the coupling-notches 36, so that the subsequent forward movement of the feed-bar member 29 will be an idle one, as shown in Fig. 8, and will not impart movement to the feed-bar member 27, with the result that the blank already positioned between the dies 12 and 14 will not be moved therefrom and replaced by another blank, but will be subjected to the additional, or second, die action. Near the conclusion of this second revolution of the feed-cam 34, the plunger 47 will again engage the star-wheel 46 and impart to it, as well as to the unlatching-cam 43, another quarter-turn, thereby permitting the retirement of the uncoupling-slide 40 under the urge of its spring 44, and the consequent reentrance of the latches 35 into the coupling-notches 36, whereby the feed-bar members 27 and 29 will again be coupled for unitary movement. So long as the plunger 47 is in its extended position, this cycle of alternate idle and feeding actions of the feed-cam 34 will take place. If, however, the plunger 47 is retracted into this position, as clearly shown in Fig. 6, it will fail to engage the star-wheel, and the two feed-bar members 27 and 29 may remain coupled, so as to produce a feeding movement of the feed-slide 19 for every revolution of the drive-shaft 16, and hence for every action of the dies 12 and 14, whereby the blanks are each subjected to but one embossing action.

It will thus be seen that by my invention a blank to be embossed may, at the option of the operator, be subjected to either a single or a double action of the embossing press.

I claim:

1. A feed-mechanism for embossing presses, comprising an actuating member; a blank-feeding member; connections between said actuating member and blank-feeding member, including two relatively-movable parts; and means for automatically coupling and uncoupling the said parts in

continuously-alternating cycles, whereby the blank-feeding member may be automatically rendered inoperative during one movement of the actuating member and automatically restored to operativeness during another movement thereof.

2. A feed - mechanism for embossing presses, comprising an actuating member; a blank-feeding member; connections between said actuating member and blank-feeding member, including two relatively-movable parts; coupling means adapted to couple said parts together; and manually-settable coupling control-means having active and retired positions, whereby the blank-feeding member may be automatically rendered inoperative during one movement of the actuating member or operated during each movement of said actuating member.

3. A feed - mechanism for embossing presses, comprising an actuating member; a blank-feeding member; connections between said actuating member and blank-feeding member, including two relatively-movable reciprocating bars; latches for coupling said bars together; a latch-operating member for retiring said latches for uncoupling said bars; and means driven by the said actuating member for periodically moving said latch-operating member, whereby the blank-feeding member may be automatically rendered inoperative during one movement of the actuating member.

4. A feed - mechanism for embossing presses, comprising an actuating member; a blank-feeding member; connections between said actuating member and blank-feeding member, including two relatively-telescoping reciprocating parts; latches for coupling the said parts together; a latch-operating member for retiring said latches for uncoupling the said telescoping parts; and means driven by the said actuating member for periodically moving said latch-operating member, whereby the blank-feeding member may be automatically rendered inoperative during one movement of the actuating member.

5. A feed - mechanism for embossing presses, comprising an actuating member; a blank-feeding member; connections between said actuating member and blank-feeding member, including two relatively-movable reciprocating parts; latches carried by one of the said reciprocating parts for coupling said parts together; a latch-operating member also carried by one of the said reciprocating parts for retiring said latches for uncoupling said parts; and means driven by the said actuating member for periodically moving said latch-operating member, whereby the blank-feeding member may be automatically rendered inoperative during one movement of the actuating member.

6. A feed - mechanism for embossing

presses, comprising an actuating cam; a blank-feeding member; connections between said actuating cam and blank-feeding member, including two relatively-movable parts; latches for coupling said parts together; a latch-operating member carried by one of the said parts for retiring said latches for uncoupling the said relatively-movable parts; and a latch-retracting cam co-acting with the said latch-operating member and itself operated to effect the movement of the latch-operating member by the said actuating cam, whereby the blank-feeding member may be automatically rendered inoperative during one movement of the actuating cam.

7. A feed - mechanism for embossing presses, comprising an actuating cam; a blank-feeding member; connections between said actuating cam and the blank-feeding member, including two relatively-movable reciprocating bars, one of which is connected to the said actuating member and the other of which is connected to said blank-feeding member; latches for coupling the said bars together; and a latch-operating member actuated by the said cam for retiring said latches for uncoupling the said bars, whereby the blank-feeding member may be automatically rendered inoperative during one movement of the actuating cam.

8. A feed - mechanism for embossing presses, comprising an actuating cam; a blank-feeding member; connections between said actuating cam and the blank-feeding member, including inner and outer relatively-movable reciprocating bars, the former of which is connected to the said actuating cam and the latter to the said blank-feeding member; latches carried by the outer bar for coupling the said bars together; and a latch-operating member carried by the inner bar for retiring the said latches for uncoupling the said bars, whereby the blank-feeding member may be automatically rendered inoperative during one movement of the actuating cam.

9. A feed - mechanism for embossing presses, comprising an actuating cam; a blank-feeding member; connections between the said actuating cam and blank-feeding mechanism, including two relatively-movable parts; latches adapted to couple said parts together; a latch-operating member carried by one of the said parts for retiring the said latches for uncoupling the said relatively-movable parts; a latch-retracting cam co-acting with said latch-operating member; a star-wheel for driving said latch-retracting cam; and a retractable plunger carried by said actuating cam and adapted to engage the said star-wheel, whereby the blank-feeding member may be automatically rendered inoperative during one movement of the actuating cam.

10. A feed - mechanism for embossing

presses, comprising an actuating member; a blank-feeding member; connections between said actuating member and blank-feeding member, including two relatively-movable parts; means for coupling said parts together; and an intermittently-movable mechanism for intermittently disengaging the said coupling means, whereby the blank-feeding member may be automatically rendered inoperative during one movement of the actuating member.

11. A feed - mechanism for embossing presses, comprising an actuating member; a blank-feeding member; connections between

said actuating member and blank-feeding member, including two relatively-movable parts; and means for automatically causing one of the said parts to move independent of the other part during one cycle of the said actuating member and to move together during another cycle of the said actuating member, whereby the blank-feeding member may be automatically rendered inoperative during one movement of the actuating member.

In testimony whereof, I have signed this 25 specification.

JOHN R. WHEELER.
